Primary Examiner — Joseph Kukella*Assistant Examiner* — Arva P Adams(74) *Attorney, Agent, or Firm* — Daylight Law, P.C.(57) **CLAIM**

The ornamental design for a beverage dispenser, as shown and described.

DESCRIPTION

FIG. 1 is a top-front-right perspective view of a beverage dispenser showing our new design;

FIG. 2 is a bottom-front-right perspective view thereof;

FIG. 3 is a front view thereof;

FIG. 4 is a left-side view thereof;

FIG. 5 is a back view thereof;

FIG. 6 is a right-side view thereof;

FIG. 7 is a top view thereof; and,

FIG. 8 is a bottom view thereof.

The broken lines in FIGS. 1–8 depict portions of the beverage dispenser that form no part of the claimed design.

1 Claim, 8 Drawing Sheets(56)
